(57) **CLAIM**

The ornamental design for a cat scratcher, as shown and described.

DESCRIPTION

FIG. 1 is a perspective view of a cat scratcher showing my new design;

FIG. 2 is a front view of the cat scratcher of FIG. 1;

FIG. 3 is a rear view of the cat scratcher of FIG. 1;

FIG. 4 is a left side view of the cat scratcher of FIG. 1;

FIG. 5 is a right side view of the cat scratcher of FIG. 1;

FIG. 6 is a top plan view of the cat scratcher of FIG. 1;

FIG. 7 is a bottom plan view of the cat scratcher of FIG. 1;

FIG. 8 is an exploded perspective view of the cat scratcher of the present invention;

FIG. 9 is a top plan view of the horizontal segment shown in FIG. 8;

FIG. 10 is a bottom plan view of the horizontal segment shown in FIG. 8;

FIG. 11 is a right side view of the horizontal segment shown in FIG. 8;

FIG. 12 is a left side view of the horizontal segment shown in FIG. 8;

FIG. 13 is a front view of the horizontal segment shown in FIG. 8;

FIG. 14 is a rear view of the horizontal segment shown in FIG. 8;

FIG. 15 is a front view of the vertical segment shown in FIG. 8;

FIG. 16 is a rear view of the vertical segment shown in FIG. 8;

FIG. 17 is left side view of the vertical segment shown in FIG. 8;

FIG. 18 is a right side view of the vertical segment shown in FIG. 8;

FIG. 19 is a top plan view of the vertical segment shown in FIG. 8; and,

FIG. 20 is a bottom plan view of the vertical segment shown in FIG. 8.
